UNITED STATES PATENT OFFICE

153,328

DESIGN FOR A TABLE LAMP

Fred W. Timberlake, Lubbock, Tex.

Application May 13, 1948, Serial No. 146,354

Term of patent 7 years

(Cl. D48—20)

To all whom it may concern:

Be it known that I, Fred W. Timberlake, a citizen of the United States, residing at Lubbock, in the county of Lubbock and State of Texas, have invented a new, original, and ornamental Design for a Table Lamp, of which the following is a specification, reference being had to the accompanying drawing, forming part thereof.

I claim:

The ornamental design for a table lamp, as shown.

FRED W. TIMBERLAKE.
